UNITED STATES PATENT OFFICE.

JOSEPH CAMERON, OF CYNTHIANA, AND JOHN S. JUDSON AND WILLARD S. JUDSON, OF SPRINGFIELD, OHIO, ASSIGNEES TO THE CAMERON HARROW AND WAGON COMPANY, OF CHICAGO, ILLINOIS.

DUMPING-WAGON.

SPECIFICATION forming part of Letters Patent No. 380,277, dated March 27, 1883.

Application filed June 4, 1887. Serial No. 240,235. (No model.)

To all whom it may concern:

Be it known that we, JOSEPH CAMERON, of Cynthiana, Pike county, and JOHN S. JUDSON and WILLARD S. JUDSON, of Springfield, Clark county, all citizens of the United States and the State of Ohio, have invented certain new and useful Improvements in Dumping-Wagons, of which the following is a specification.

Our invention relates to improvements in dumping-wagons, and also relates in its nature to improvements upon the dumping-wagon set forth in Patent, No. 329,714, dated November 3, 1885, to Joseph Cameron.

The object of this invention is to provide a wagon-bed the bottom of which is composed of a series of hinged slats arranged in connection with a series of levers and side bars, whereby the slats may be turned down and thus open the bottom of the bed for the purpose of dumping the material of which the load therein is composed.

The invention consists, first, in a novel arrangement of the slats in connection with the hinges thereof.

It further consists in a novel arrangement of the side bars adapted to open and close the said slats.

It further consists in a novel arrangement of the lifting-lever in connection with the side bars, whereby the slats are automatically locked in position when the said slats are closed.

It further consists in a novel arrangement of the hoods or coverings used for covering the space between the slats where openings occur between the same, over the bolsters, &c.

It further consists in various constructions and combinations of parts, hereinafter described, and set forth in the claims.

In the accompanying drawings, Figure 1 is a side elevation view of a wagon embodying our invention, one pair of slats being shown open in dotted lines. Fig. 2 is a longitudinal sectional view of the same. Fig. 3 is a bottom

view of one pair of slats, showing the arrangement of the hinges and the method of connecting the side bars thereto. Fig. 4 is an end view of the slats and the hinges therefor. Fig. 5 is a sectional view through the side of the bed or box, showing the method of attaching the bearings for the slats. Fig. 6 is a perspective view of a portion of the slats forming the bottom of the bed, showing the arrangement of the side bars connected thereto. Fig. 7 is a partial side elevation view showing the method of connecting the main bar to the hand-lever. Fig. 8 is a detailed view in section of the same. Fig. 9 is a detailed view showing a modification of the same. Fig. 10 is a partial sectional view showing the method of attaching the slats over the bolster. Fig. 11 is a side elevation view of the same. Fig. 12 is a perspective view showing the slats formed of sheet metal. Figs. 13 and 14 are partial sectional views of the bed, showing the method of forming the hoods or covering over the space between the slats over the bolster.

Like parts are indicated by similar letters of reference throughout the several views.

In the accompanying drawings, A A represent the main body of the box or bed, the sides of which are preferably formed in two parts, A' and A², which are connected together by side strips, a, and the end strips, a' a', (see Fig. 2,) or in any other convenient manner. The slats B, which form the bottom of the bed, are hinged to the lower portion, A², thereof by journals b, supported in bearing-boxes b', secured on the lower edge of the said side piece A². These bearing-boxes are preferably held in place by bolts b², which extend through the side piece A², as shown in Fig. 5. Extended upward from near the bottom of the bed is a series of parallel bars, c, each of which is pivoted at the top to a main bar, d, which is in turn connected by means of a connecting-bar, e, to the hand-lever f.

Each of the slats B is provided with a trunnion, *g*, near the outer edge thereof, to which is attached the lower end of a supporting-bar, *h*, the said supporting-bars being each pivoted 5 at their upper end to the main bar *d*.

In order that the bed or box may be readily applied to any wagon, we provide at either end a false bolster, *D*, grooved at each end to receive the ordinary standard, *i*, of the wagon.

10 The bed or box A A is supported upon the false bolster *D* by means of brackets *D'* on either side thereof, provided with a bifurcated bottom, *j*, adapted to project over the bolster. These brackets *D'* are preferably formed of 15 metal, cast in a single piece, as shown in Figs. 10 and 11, with the bearings *b'* therein for the journals *b* of the slats, which are hinged on either side of the bolster. It is evident that these brackets may be made of wood and provided with plates *j'* to form the bearings for 20 the said journals, as shown in Fig. 1. It will be seen that a space is left between the slats over the bolster, above which we provide a hood, *E*, so that the material forming the load 25 is directed down between the slats when they are dropped for dumping. At a short distance back of the front bolster *D* we provide in the bottom of the box or bed an opening, *F*, adapted to receive the wheels of the wagon 30 in turning corners, &c. This space is also provided with a cone or covering, *E'*. In the rear of the rear bolster, and between the said bolster and the opening *F*, we preferably arrange the slats in pairs, and in order that the 35 slats may be placed as compactly as possible we hinge the respective slats of each pair together and to a common journal, *b*, as shown in Figs. 3, 6, and 12.

When the dumping-slats are made of wood, 40 we form the hinge of each pair in two parts, *B'* and *B''*, and provide each part thereof with a projection at the outer end adapted to form the trunnion *g*, to which the supporting-bars are attached. The part *B''* of the hinge is preferably formed of a U shape, having the two 45 projecting trunnions *b* and *g*, which trunnions are preferably made of the same size and shape, so that, if desired, they may be reversed and placed on the opposite end of the slats, in 50 which case the bearing *b* becomes the trunnion *g*, and vice versa. The part *B'* of the hinge is preferably formed of a T shape, having an eye, *b''*, adapted to slip over the trunnion *b*, as shown in Figs. 3 and 4.

55 The parallel bars *c*, to the upper ends of which the main bar *d* is attached, are preferably pivoted directly on the trunnions or journals *b* of the respective slats, the supporting-bars being extended from the main bar to the 60 respective trunnions *g* on the said slats, one of said bars being preferably connected to the main bar at the same point at which the par-

allel bar is attached. It will be seen now that as the lifting-lever *f*, which is pivoted to the side of the box or bed A A, is turned back 65 upon its pivot, the main bar *d* will be forced backwardly and downwardly by means of the parallel bars *c*, and through the medium of the supporting-bars *h* will cause the slats to revolve about their center, thus opening the 70 bottom of the box or bed to dump the load.

The point at which the hand-lever *f* is pivoted to the bed or box and the point of connection between the connecting-rod *e* and the main bar *d* and the point of connection between the said connecting-rod *e* and the hand-lever *f* are so arranged that as the hand-lever *f* approaches the limit of its movement in closing the slats the three points are in a straight line, so that as the lever *f* is pressed down 80 against the stop *f'* the connecting-bar *e* passes just below the point at which the lifting-lever is pivoted, thus forming an automatic lock by which the said lever is held securely in place when the slats are in a closed position. 85

In order that the slats may be completely closed when the hand-lever *f* is in the position described, and in order to compensate for any wear on the different parts, we make the connecting-bar *e* adjustable in length. This may 90 be accomplished, as shown in Figs. 7 and 8, by forming the connecting-bar *e* in two parts joined by a coupling, *e'*, having right and left threads in the respective ends thereof adapted to engage with the ends of the respective parts 95 of the said connecting-bar, which are correspondingly threaded. In Fig. 9 the same result is accomplished by providing a small angular clip pivoted to the lever *f* and provided with a wing, *e''*, through which the connecting-bar 100 *e* is passed, the said bar being first screw-threaded and provided on either side of the said wing with adjustable nuts *e'''*. By this means it will be seen that any wear on the journals or pivots may be readily compensated 105 for and the slats brought securely to their position when the hand-lever *f* is forced against the stop *f'*.

It is obvious that the slats may be formed of wood or metal, as desired. When formed of wood, the hinges are preferably placed on the bottom of the slats, so that when closed the said slats come flush with the lower edges of the sides of the bed. When the wooden slats are used, we preferably place a small hood, *E''*, 115 over each of the journals of the said slats, whereby the material forming the load is directed on either side of the said journals and prevented from entering between the said slats, and thus interfering with the closing of the 120 same. When the metal slats are used, the hinges are formed by bending the metal around to form an eye or sleeve, as shown in Figs. 12, 13, and 14, the journal *b* which connects the

respective parts being adapted to pass entirely through the openings or eyes thus formed in the said slats. By this construction the hood E, over the bolster, and the hood E', over the 5 space F, may be formed by hinging additional slats, B³, to the journals b and bringing the said slats together at the top and connecting the same by a rod, b⁴. By this construction it will be seen that by removing the rod b⁴ and one of the journals b at the bottom one of the slats B³ may be removed and the other one dropped 10 down and joined to the main slat B, as shown in Fig. 14, thus entirely closing the bottom of the bed and dispensing with the cones, leaving 15 the bottom of the bed perfectly even, so that it will not differ materially from an ordinary bed. By this construction the bed may readily be adapted for ordinary use in case it is desired to remove the load or material therein 20 by shoveling or otherwise, small plates being provided for closing the opening F when the hood over the same is turned down, as described.

It is evident that the constructions herein described admit of various modifications. We have shown the bed or box formed in two parts, the sides of which are secured together by side strips and by bolts which pass through the said side pieces, as indicated in dotted 25 lines in Fig. 5. It is evident, however, that the sides may be formed in one piece or in many pieces, as desired.

By providing the opening F with the hood over the same and the slats arranged on either 30 side thereof means are provided whereby the wagon may turn corners readily.

It is evident that the arrangement of the slats may be varied, as desired. Instead of the single slats near the front of the bed, the slats 35 may be arranged in pairs, as in the rear portion, the said slats being varied in size, as required; or, if desired, the slats may all be arranged singly, the connection with the main supporting-bars being as described.

40 By providing the false bolsters D in the manner described, having the grooves i² in the end thereof, adapted to project over the standard i in ordinary wagons, the bed may be readily removed or replaced on the running-gear without 45 disarranging any of its parts, and the wagon used for any desired purpose.

It is evident that the construction herein described may be applied to railway-cars or to other vehicles, and we do not, therefore, limit 50 ourselves to their use in connection with wagon-beds alone, but claim them for all purposes for which they are applicable.

Having thus described our invention, we claim—

55 1. A bed or box the bottom of which is formed of hinged slats each provided with a supporting-trunnion, a main bar extending

longitudinally along the side of said box and connected at intervals to parallel bars journaled at one end concentric with the journals 60 of the said slats, and a supporting-bar extending from said main bar to the trunnions on the said slats, substantially as set forth.

2. A bed or box the bottom of which is provided with a series of slats arranged in pairs, 70 each slat of the respective pairs being hinged to a common journal provided with a projecting trunnion adapted to project from the side of the said box, supporting-bars connected to said trunnion, and a series of side bars and a 75 hand-lever connected thereto, whereby the said slats are adapted to be opened and closed by said hand-lever, substantially as set forth.

3. A bed or box the bottom of which is formed of a series of hinged slats arranged in 80 pairs, each of said slats being provided with a projecting trunnion, a series of parallel bars hinged to the journals of said slats, a main bar connecting the said parallel bars and pivoted thereto, and supporting-bars extending 85 from the said main bar to each of the said slats, and means for moving said main bar longitudinally, substantially as and for the purpose set forth.

4. In a dumping box or bed, a series of slats 90 arranged in pairs in the bottom thereof, each of the said slats of the respective pairs being hinged to a common journal, and a main longitudinal bar pivoted to a series of parallel bars and connected by suitable means to each of 95 the said slats, the said parallel bars being each hinged on the same journal which forms the bearing for the said slats, substantially as and for the purpose set forth.

5. In a dumping box or bed, the hinged 100 slats and the supporting-bars connected to said slats and the main bar, the pivoted hand-lever, and a connecting-bar adapted to connect said hand-lever and main bar in such a manner that as the slats are drawn to their 105 normal position the connecting-bar is adapted to pass the point at which the hand-lever is pivoted, and thus form an automatic lock for said slats, substantially as set forth.

6. In a dumping bed or box, the hinged 110 slats connected by a series of side bars to a main bar, a hand-lever connected to said main bar by a connecting-rod adapted to pass centers, as described, and means for adjusting the length of said connecting-rod, substantially 115 as set forth.

7. In a dumping bed or box the bottom of which is formed of a series of slats, an opening between the said slats into which the wheels of the running-gear of said bed are adapted 120 to turn, and a hood or cone over said opening, substantially as set forth.

8. In a dumping box or bed the bottom of which is provided with a series of hinged slats,

a hinged cone adapted to form a hood above the space between the respective slats, the sides of said cone being hinged together in such a manner that one side thereof may be removed and the other side dropped down and hinged to the respective slats, and thereby close the space between the said slats, substantially as set forth.

9. A dumping bed or box the bottom of which is formed of a series of hinged slats, means for raising and lowering said slats, as described, a false bolster secured at either end of said bed or box, slats pivoted on either side of said bolster, and a hood or covering above said bolster, substantially as set forth.

10. A dumping bed or box the bottom of which is formed of a series of hinged slats, a false bolster secured at either end of said bed, brackets between said bolsters and bed, said 20 brackets being adapted to form a bearing for the slats on either side of said bolster, and a hood or covering above the said bolster and slats, substantially as set forth.

In testimony whereof we have hereunto set

our hands at the time and places hereinafter 25 noted:
